UNITED STATES PATENT OFFICE.

THOMAS J. KENNEL, OF NEAR MIDDLETOWN, OHIO.

COMBINED WAGON BOX AND RACK.

1,228,117.

Specification of Letters Patent.

Patented May 29, 1917.

Application filed September 2, 1916. Serial No. 118,213.

To all whom it may concern:

Be it known that I, THOMAS J. KENNEL, a citizen of the United States, residing near Middletown, Butler county, Ohio, have invented certain new and useful Improvements in Combined Wagon Boxes and Racks, of which the following is a specification.

This invention, pertaining to combined wagon-boxes and racks, relates to new improvements by means of which there is produced a wagon-box convertible into a rack for hay or grain-bundles, and additional improvements to secure such tightness of floor as to practically avoid the loss of grain.

The invention will be readily understood from the following description taken in connection with the accompanying drawings in which:

Figure 1 is a vertical transverse section of my improved structure in the plane of line *a* of Fig. 2:

Fig. 2 a side elevation of the structure, portions appearing in vertical longitudinal section in the plane of line *b* of Fig. 1:

Fig. 3 an elevation of the head-end of the structure:

Fig. 4 an elevation of the tail end of the structure:

Fig. 5 a perspective view of one of the braces:

Fig. 6 a vertical transverse section of a portion of the structure in the plane of line *c* of Fig. 2:

Fig. 7 a plan of one of the fastening devices employed in securing the main structure to the sub-frame: and

Fig. 8 a side view of this fastening device with its parts disengaged.

A diversity of scales is employed in the drawings.

In the drawings, giving principal attention to Fig. 1:

1, indicates a sub-frame adapted to be secured upon the bolsters of the running-gear of an ordinary farm wagon by any suitable means, this sub-frame being preferably narrowed at its forward end to permit the usual horizontal oscillating motion of the front axle:

2, a deck disposed some distance above the sub-frame and forming the floor of the wagon-box or the rack:

3, cross-sills resting upon the sub-frame and having the floor 2 secured to them, Fig.

2 illustrating the structure as being provided with four of these cross-sills:

4, the ends of the cross-sills 3, these ends extending outwardly beyond the sides of 60 floor 2:

5, the forward end-gate, permanently secured to the structure formed by the floor and cross-sills:

6, the rear end-gate, also permanently secured to the structure formed by the floor and cross-sills:

7, box-sides having pivotal connection with the cross-sills and adapted to take vertical position against the side edges of the 70 end-gates and form the sides of the wagon-box, or to be turned outwardly and downwardly over the outwardly extended ends of the cross-sills:

8, top side-boards adapted to be secured 75 to the structure over the box-sides 7 when the latter are in vertical position:

9, vertical ribs, preferably of angle irons, arranged in pairs, these vertical ribs being permanently secured against the outer surfaces of the box-sides and having their lower ends extending below the lower surface of floor 2 and straddling the cross-sills:

10, substantially horizontal slots through 85 the cross-sills where they are straddled by the lower ends of ribs 9:

11, a horizontal pivot through each pair of ribs 9 and passing through the slot in the appropriate cross-sill:

12, a stop upon the outwardly projecting end of each of the cross-sills, these stops being designed to limit the downward motion of the box-sides when they are folded down to form a rack, the stops preventing 95 the box-sides from going clear down to horizontal position, thus giving to the general rack floor a level center portion in conjunction with side portions inclining outwardly, the preference being that these stops are in 100 the form of bent irons secured to the tops of the outwardly extending portions of the cross-sills:

13, braces, each having its upper end pivoted to a pair of the ribs 9 and having 105 its foot supported by the appropriate stop 12 on which the foot of the brace rests:

14, bails, one pivoted to each pair of ribs 9 near the base of the sideboard, the outer end of the bail engaging outside of and 110 forming a horizontal tie between the base of the box-side and the foot of the brace:

- 15, hooks secured to the inner surfaces of the end-gates within the box-sides, such hooks being located near the top edges of the box-sides and again at about the center of width of the top sideboards: and
- 16, a rod at each of the hooks 15, these rods passing through the box-sides and top sideboards, each having a hook at its inner end to engage appropriate hook 15 and having a hand-nut screwed on its outer end.
- 10 When the structure is to be used as a wagon-box, the box-sides take the vertical position indicated at the right in Fig. 1, and if it be desired that the wagon-box be deeper than the box-sides, then the top sideboards are added, the rods 16 being hooked to hooks 15 and their nuts tightened up. The box sides and top sideboards are thus secured tightly and firmly against the ends 15 of the end-gates, the bases of the box-sides resting upon floor 2 forming a tight joint, and the outward movement of the bases of the box-sides being prevented by pivots 11 reaching the outer ends of the slots 10.
- 20 As there are a number of pairs of the vertical ribs along each box-side the bases of the box-sides are firmly supported against outward movement. The braces 13 steady the box-sides against outward bulging at 25 points between the end-gates. By this construction there is produced a grain-tight wagon-box with its sides well braced and permitting of satisfactory strength with comparatively thin box-sides. The braces 13 have their upper ends pivoted between their 30 pairs of ribs 9, and the bails 14 are of a width sufficient to straddle the braces 13 and to swing down and over the projecting ends of the cross-sills. The permanent end-gates 5 and 6 are as high as the wagon-box 35 formed by the box-sides and top sideboards.
- When the structure is to be employed as a rack, the top sideboards are removed and the hook-rods of the box-sides are released, 40 after which the box-sides are turned outwardly and downwardly upon the pivots 11, the box-sides coming to rest upon the stops 12 and receiving firm support from the projecting ends of the cross-sills, as seen at the 45 left in Fig. 1. When the box-sides are thus turned down upon the pivots 11, a longitudinal crack will be produced at each side-edge of floor 2, and these cracks might permit the loss of grain sifting from grain 50 bundles. To avoid this, the box-sides, after they have been turned down, are moved inwardly till their inner edges make tight joints with the outer edges of floor 2. When the box-sides are thus shifted inwardly they 55 are secured in such position by means to be described later.
- Continuing with the drawings, and giving particular attention to Figs. 2, 7 and 8:—
- 60 17, indicates loops secured to the sub-

frame at the front of the cross-sills and presenting themselves above the sub-frame:

18, tongues secured to the front of the cross-sills and adapted to engage within the loops 17:

19, strong vertical battens secured to the outside of the rear end-gate near the side edges thereof and extending down past the cross-sill at the end and against the rear end of the sub-frame:

20, straps securing the battens firmly to the cross-sill at the rear end of the structure:

21, removable straps securing the bases of the battens to the rear end of the sub-frame:

22, vertical stakes disposed against the outer surface of the rear end-gate, against the inner edges of battens 19 and having their lower ends normally engaged by straps 20 and 21 out of which, however, the stakes 85 can be drawn upwardly:

23, a strap securing each of the stakes slidably to the rear end-gates:

24, a similar strap for each of the stakes, but provided with a clamp-screw:

25, a door in the lower portion of the rear end-gate, this door having its upper edge hinged in a door-opening in the end-gate and having a length less than the distance between battens 19 and greater than the 95 distance between stakes 22:

26, a cross-piece secured under floor 2, preferably at mid-length of the floor:

27, a bail pivoted to each end of this cross-piece on a horizontal pivot:

28, a tongue secured to the lower edge of each box-side at its outer surface, these tongues being adapted to be engaged by the bails 27:

29, horizontal hand-screws through the 105 bails and adapted to press the tongues inwardly:

30, a pair of battens firmly secured to the outer surface of the forward end-gate:

31, a ladder-structure having its vertical 110 rails fitted to slide between the battens 30:

32, a cross-bar secured to the battens 30 and crossing the front of the ladder-structure:

33, a second cross-bar, above the first one: 115 and

34, hand-screws by means of which cross-bar 33 may be clamped against the ladder-structure to hold the latter in adjusted vertical position.

It being desired to mount the main structure on the sub-frame, it is set over the sub-frame with the cross-sills resting on the sub-frame, after which it is pushed forward on the sub-frame so that the tongues 18 engage 125 the loops 17, after which straps 21 are applied. The main structure thus becomes secured to the sub-frame in such manner as to prevent longitudinal or lateral shifting.

Looking at Fig. 4, stakes 22 are normally 130

in downward position, that is to say, when the structure is to be used as a wagon-box, and when the stakes are in this position, they engage outside door 25 and hold it closed. 5 When the door is to be opened, as in dumping grain, straps 24 are relieved from their clamping office and the stakes may be raised, as indicated at the right in Fig. 4, so that their lower ends are free of the door, thus 10 permitting the door to swing open. When the structure is to be used as a rack then the stakes may be secured in any desired elevated position within their limits of vertical adjustment. If hay or straw is being 15 hauled then the stakes may even be elevated so as to be free of the door, as any accidental opening of the door would do no harm.

When the box-sides have been swung 20 downward, in the manner heretofore described, the bails 27 are turned up and outside tongues 28 and the hand-screws may be employed in forcing and holding the inner edges of the box-sides closely and firmly to 25 the outer edges of the box-floor.

Referring to Fig. 3, when the structure is being employed as a wagon-box, the ladder-structure will preferably be in its downward position, but when the structure is to 30 be used as a rack then hand-screws 34 are loosened and the ladder-structure elevated, say till the bases of its side rails are even with the bottom of cross-bar 32, after which the ladder-structure may be clamped in its 35 elevated position.

I claim:—

1. A combined wagon-box and rack comprising, a box-floor, a cross-sill disposed under the floor at an intermediate portion 40 of its length and having the floor secured to it and having its ends projecting beyond the side edges of the floor, box-sides having pivotal connection with the projecting ends of the cross-sill and adapted to occupy a 45 vertical position or to be turned down to substantially horizontal position over the projecting ends of the cross-sill, swinging braces having their upper ends pivotally connected with the box sides and having 50 their lower ends adapted to rest upon and be supported by the projecting ends of the sill when the box sides are in vertical position and to swing off of and project idly down below said projecting ends when the 55 box sides are down, and horizontal ties having their inner ends pivoted to the box-sides and having their outer ends adapted to engage exterior to the lower ends of the braces when the box-sides are in vertical 60 position, combined substantially as set forth.

2. A combined wagon-box and rack comprising, a box-floor, a plurality of cross-sills having the floor secured to them and having their ends projecting beyond the 65 side-edges of the floor, end-gates secured to

the cross-sills at the ends of the floor, box-sides having pivotal connection with the cross-sills and adapted to turn down to position over the projecting ends of the cross-sills, tongues carried by the bases of the 70 box-sides, screws adapted to engage said tongues and hold the inner edges of the box-sides against the edges of the floor when the box-sides are turned down, and means for locking the box-sides in vertical position, combined substantially as set forth. 75

3. A combined wagon-box and rack comprising, a box-floor, a plurality of cross-sills having the floor secured to them and having their ends projecting beyond the 80 side-edges of the floor, end-gates secured to the cross-sills at the ends of the floor, box-sides having pivotal connection with the cross-sills and adapted to turn down to position over the projecting ends of the 85 cross-sills, means for locking the box-sides in position, an outwardly opening door having its upper edge hinged in a door-opening in the base of the rear end-gate, vertically disposed stakes carried by the 90 rear end-gate against the outer surface of said door but adapted to slide upwardly to release the door, and means for securing said stakes in adjusted position, combined substantially as set forth. 95

4. A combined wagon-box and rack comprising, a box-floor, a plurality of cross-sills having the floor secured to them and having their ends projecting beyond the side-edges of the floor, end-gates secured to the cross-sills at the ends of the floor, box-sides having pivotal connection with the cross-sills and adapted to turn down to position over the projecting ends of the 100 cross-sills, a pair of ribs secured to the side-boards at each of the cross-sills and having their feet straddling the cross-sills, pivots uniting the feet of the ribs to the cross-sills, a brace having its upper end pivoted to each pair of ribs and having its lower 105 end supported by a projecting end of the appropriate cross-sills, and a bail pivoted to each pair of ribs and engaging outside of the feet of the brace pivoted to that pair of ribs, combined substantially as set 110 forth. 115

5. A combined wagon-box and rack comprising, a box-floor, a plurality of cross-sills having the floor secured to them and having their ends projecting beyond the side edges of the floor, end-gates secured to the cross-sills at the ends of the floor, box-sides having pivotal connection with the cross-sills and adapted to stand 120 vertically and to turn down to position over the projecting ends of the cross-sills, a pair of vertical battens secured to the forward end-gate, a ladder fitted to slide vertically between said battens and against the end-gate and to occupy selective positions inde. 125 130

pendent of the position of the box-sides, and an adjustable clamp secured to the battens and extending across the face of the ladder and adapted to serve in clamping 5 the ladder against the end-gate, combined substantially as set forth.

6. A combined wagon-box and rack comprising, a box-floor, a plurality of cross-sills having the floor secured to them and 10 having their ends projecting beyond the side edges of the floor and provided with substantially horizontal slots extending transversely through them under the edges of the floor and partly under the floor and 15 partly outwardly beyond the edges of the

floor, box-sides adapted to rest upon the floor at its outer edges and to turn down to substantially horizontal position on the projecting ends of the cross-sills, ribs secured to the outer surfaces of the box-sides 20 and projecting down across said slots, and pivots carried by said ribs in fixed position relative thereto and engaging said slots and always vertically supported by the lower surface of the slots, combined substantially 25 as set forth.

THOMAS J. KENNEL.
